STENCILING MACHINE

Bradley K. Holbrook, Berkeley, Calif., assignor
to Owens-Illinois Pacific Coast Company, a
corporation of Delaware

Application June 12, 1941, Serial No. 397,782

7 Claims. (Cl. 101—124)

The present invention relates to decorating machines of the silk screen stencil type and more particularly to a machine for applying surface decoration of ceramic or vitreous enamel material to a cylindrical surface such as the body of a bottle or the like, or to a frusto-conical surface such as, for instance, the shoulder of a bottle.

In general the usual decorating or stenciling machine is constructed for a single purpose, either for decorating the cylindrical surface of the body of a bottle or for the sole purpose of decorating a frusto-conically shaped surface thereof. Ordinarily therefore separate machines are employed where the bottle or article requires both shoulder and body decoration. Where the volume of articles to be decorated is relatively small, the expense of separate, or additional machines cannot be justified and may be eliminated by the use of a universal type of machine which forms the subject of this application. As will be brought out more fully presently, I have provided a machine which is readily adaptable for decorating either the shoulder or body of a bottle or similar article, the changing from one form to the other requiring only a simple operation.

It is the primary object of the invention to provide a decorating machine of relatively simple construction which is semi-automatic in operation and which may be readily converted for decorating either cylindrical or frusto-conical articles.

Another object of the invention is the provision of unified controlling means whereby one cycle of operation is completed upon each operation of the treadle.

Other objects and advantages will be apparent and in part pointed out hereinafter.

In the accompanying drawings:

Fig. 1 is a plan view of a shoulder decorating machine embodying my invention.

Fig. 2 is a plan view of the machine set up for decorating cylindrical articles.

Fig. 3 is a vertical sectional view through the machine taken substantially along the line 3—3 of Fig. 1.

Fig. 4 is a vertical transverse sectional view taken substantially in the vertical plane of the squeegee and illustrating a bottle in shoulder decorating position.

Fig. 5 is a vertical transverse sectional view illustrating the cylindrical body stenciling apparatus.

Fig. 6 is a front elevational view of a portion of the machine, parts being shown in section.

Fig. 7 is a vertical sectional view taken substantially along the line 7—7 of Fig. 6.

Fig. 8 is an elevational view of the operating air control valve.

5 Referring to Figs. 1 and 3 in particular, the machine comprises a wheeled base, or supporting frame 10, upon which is provided a table surface 11 or platform above which the decorating mechanism D is mounted. The frame 10 also provides support for the operating control means as will be brought out presently.

10 The mechanism D includes a pair of parallel rails 12 (Figs. 1, 2, and 4) supported along and over one edge of the frame 10 on upright members 13, or legs, one pair of which forms the front corners of the frame. A vertical post 15 extends upwardly from the frame 10 and is connected at its upper end to the rearward rail 12 medially thereof. The post forms the support for one 15 end of a bracket 16 which carries a part of the driving mechanism and which rests near its other or forward end on the forward rail 12 to which it is bolted.

15 In the decoration of rounded or tapering surfaces such as a frusto-conical bottle shoulder, it is necessary that the stencil screen oscillate about a pivot, the point of which is coincident with the apex of the cone. In order to accomplish this, I provide a vertical shaft 17 (Figs. 3 and 4) journaled in bearings at the forward end of the bracket 16. A drive gear 18 keyed to the upper 20 end of the shaft meshes with one of a pair of driving racks 19 which serve to oscillate the shaft. A semi-circular stencil screen frame 20 carried at the lower end of the shaft 17 is thereby oscillated in a horizontal plane.

25 An article to be decorated, such as a bottle B (Figs. 3 and 4) is rotatively supported in a movable article carrier assembly 22. The carrier comprises a bracket 23 bolted to the table 11 and arranged to support a bar 24 pivoted thereto for vertical swinging movement. A vertical longitudinal slot 25 is provided in the bar 24 for adjustably receiving bottle supporting yokes 26. 30 These yokes are readily adjustable to position the bottle in decorating relation with the screen when the carrier is raised from the loading position, as illustrated in Fig. 3 to the decorating position shown in Fig. 4. An adjustable stop member 27 or guide holds the bottle against longitudinal slipping during the decorating operation.

35 A squeegee 28 carried by a rock arm 29 functions to apply coloring material through the perforated areas of the screen onto the article. The

arm is pivoted on a horizontal pin 30 which is journalled in a bearing 31 on the bracket 16 and said bearing also including a pair of guides 19^a for the driving racks 19. Frictional contact between the screen and bottle incident to engagement of the screen with the squeegee and bottle is such that when the screen is oscillated, the bottle is rotated about its own axis.

Means for driving the racks 19 to oscillate the screen comprises an air operated piston motor 33 (Figs. 6 and 7) having a piston 34 and rod 35 therein. The motor is mounted on a plate 36 spanning the rails 12 at one end of the machine. The racks 19 are bolted at one end to a head 37 carried by the piston rod 35 and have a spacing member at the other end thereof. The bearing 31 supports the racks in positive alignment with the gear 18 and a gear 39 which drives a body screen carriage soon to be described. The length of the piston stroke may be regulated by means of a rod 40 disposed parallel with piston rod and connected at one end to the head 37. The rod extends through a boss 41 formed on the motor cylinder and is threaded at both ends to receive lock nuts 42 which may be adjusted as desired.

Air under pressure for operating the motor is supplied through pipes 43 under control of a rotary valve 44 (Fig. 8) of conventional type. Such a valve is illustrated in Patent #2,113,576 to Denelsbeck, dated April 12, 1938, to which reference may be had. Means for actuating the valve 44 and driving mechanism comprises a foot treadle 45 (Fig. 3) pivoted within the frame 10 at the base of the post 15. An intermediate lever 46 also pivoted on the post 15 is connected at one end to the treadle 45 by means of a rod 47 and by which the lever is rocked. A turn-buckle 48 between the lever 46 and bar 24 of the bottle carrier may be adjusted to properly locate the article in decorating position when the treadle is depressed. The opposite end of the lever 46 is connected to the squeegee rock arm 29 by a rod 49 and to one end of a valve operating lever 50 by a rod 51. The lever 50 is also pivoted to the post 15. A rod 52 connects the lever 50 with the operating arm 53 of the valve 44 and a coil spring 54 connected between the end of the lever and the platform 16 serves to return the mechanism to starting position on completion of each decorating stroke.

Figs. 2, 5, and 6 illustrate the machine as adapted for decorating cylindrical articles such as the body portion of a bottle B. The mechanism comprises a screen frame 55 supported on arms 56 which are adjustably secured by bolts 57 to a rectangular carriage 58. The carriage is adapted for horizontal sliding movement on a pair of rods 59 disposed parallel with the rails 12 and supported at either end by a bar 60 bolted between the corner legs 13. A bracket 61 bolted to the post 15 supports the rods at the center of the machine and carries a part of the weight of the screen carriage.

Movement is imparted to the carriage from the gear 39 which is keyed to a vertical shaft 63 journalled in the bracket 16 and a gear 64 at the lower end of the shaft which meshes with a rack 65 secured to the carriage. Reciprocation of one of the racks 19 thereby transmits motion to the screen for decorating the article. When cylindrical articles are being decorated, the shoulder screen 20 is removed from the shaft 17 which continues to be rotated, but ineffectively during the body decorating operation.

Depressing the treadle 45 for each decorating stroke raises the article in the carrier assembly, which may be readily adjusted so that the side of the cylindrical article lies in parallel relation

5 with the bottom of the screen and also sets in motion the squeegee and driving mechanism as heretofore described. It will be noted from the foregoing that changing the machine from one form to the other is a relatively simple matter entailing only a short time and requiring a minimum of labor.

Modifications may be resorted to within the spirit and scope of the appended claims.

I claim:

15 1. In apparatus of the character described, a table, a framework thereon including horizontal guide rods at the upper end, a slide arranged for reciprocation on said rods, means for driving said slide comprising an air operated piston motor, a driving rack operated thereby, a vertical shaft arranged at one side of said rack, a gear carried on the upper end of the shaft and meshing with said rack whereby operation of said motor causes oscillation of the shaft, a gear keyed on the lower end of the shaft and meshing with a rack carried by said slide, a stencil screen supported by and at one side of said slide and movable in a horizontal plane, a squeegee pivotally supported over the screen for operation therewith, an article holder beneath the screen arranged to support an article having a cylindrical surface in frictional contact with the screen whereby movement of the screen while such contact is maintained imparts rolling motion to the article, and a valve for controlling the motor.

2. In mechanism for reciprocating a stencil screen, a horizontal slide, arms adjustably mounted on the slide for supporting a screen, a screen thereon, a pair of horizontally spaced parallel guide rods adapted to support the slide, a rack secured to the slide, a second rack slidably mounted above said first named rack and parallel thereto, gearing forming a driving connection between said racks, an air operated piston motor for driving said second named rack, a squeegee mounted above said screen for operation therewith, a bottle holder beneath the screen adapted to support a bottle at times in frictional rolling contact with the screen, and a valve for controlling operation of the piston motor.

3. In mechanism for reciprocating a stencil screen, a horizontal slide, horizontally spaced

55 parallel guide rods supporting the slide, a screen carried by the slide and movable lengthwise in a horizontal plane, a rack on said slide, a second rack mounted above and in parallel relation with said first named rack, driving connection between said racks including a vertical shaft having gears at both ends thereof meshing with the racks, an air operated piston motor connected to the uppermost of said racks for reciprocating it, a squeegee mounted for operation with said

60 screen, an article holder beneath the screen adapted at times to hold an article to be decorated in rolling contact with the screen, a valve for controlling said piston motor, and manually operated means for moving said squeegee and holder simultaneously with actuating said valve.

4. In apparatus of the character described, a table, a framework thereon including horizontally disposed guide rods at the upper end, a slide arranged for reciprocation on said rods, means for driving said slide comprising an air

operated piston motor, a driving rack secured thereto, a vertically disposed shaft arranged at one side of said rack, a gear carried on the upper end of said shaft and meshing with said rack whereby operation of said motor causes oscillation of the shaft, a gear keyed on the lower end of the shaft, a rack carried by said slide and meshing with the last named gear, a stencil screen supported by and at one side of said slide and movable in a horizontal plane, a squeegee mounted for operation with said screen, an article holder beneath the screen, a valve for controlling said motor, and interconnected means for operating said squeegee, holder and motor.

5. In stenciling apparatus, a horizontal frame, a pair of horizontally spaced parallel racks mounted for reciprocation on the frame, means for reciprocating the racks, a gear meshing with each rack, a pair of vertical shafts supporting the gears, said shafts journaled in and extending below the frame and means provided at the lower end of each shaft for effecting operative connection between it and a stencil screen.

10 6. In stenciling apparatus, a horizontal frame, a pair of horizontally spaced parallel racks mounted for reciprocation on the frame, means for reciprocating the racks, a gear meshing with each rack, a pair of vertical shafts supporting the gears, said shafts journaled in and extending below the frame, a horizontal slide mounted adjacent to the lower end of one shaft, a rack attached to the slide, a gear secured to the lower end of said one shaft and meshing with the rack, and means facilitating attachment of a stencil screen to said slide.

15 7. In stenciling apparatus, a horizontal frame, a pair of horizontally spaced parallel racks mounted for reciprocation on the frame, means for reciprocating the racks, a gear meshing with each rack, a pair of vertical shafts supporting the gears, said shafts journaled in and extending below the frame, a gear at the lower end of one shaft, and means for supporting a screen and effecting operative connection between it and said gear.

BRADLEY K. HOLBROOK.
